[57] CLAIM

The ornamental design for a condiment dispenser or the like, as shown and described.

DESCRIPTION

FIG. 1 is an elevational view of a condiment dispenser or the like showing my new design.

FIG. 2 is a top plan view.

FIG. 3 is an elevational view of a further embodiment.

FIG. 4 is a top plan view of the embodiment shown in FIG. 3.

The bottom of the condiment dispenser or the like is substantially flat.
